ADELARD COUTURE, OF ARCTIC, RHODE ISLAND.

ROTARY OIL-BURNER.

1,295,856.

Specification of Letters Patent.

Patented Mar. 4, 1919.

Application filed November 7, 1918. Serial No. 261,503.

To all whom it may concern:

Be it known that I, ADELARD COUTURE, a citizen of the United States, residing at Arctic, in the county of Kent and State of Rhode Island, have invented a new and useful Improvement in Rotary Oil-Burners, of which the following is a specification.

This invention relates to certain new and useful improvements in rotary oil burners, and the primary object of the invention is to provide means for automatically effecting shutting off of the oil supply to the burner, should stoppage of the fan employed to supply air to the burner occur for any reason, such as breakage of the belt employed to drive the fan, or disengagement of the belt from the driving and driven elements.

Further, the invention aims to provide an oil burner which has improved oil distributing means, and which is also subjected to the action of all air entering from below so as to prevent the cool incoming air from contacting with and resultantly cooling the water legs of the heater, or other parts of the device in connection with which the burner is used.

Further and other objects will be later set forth and of themselves manifested in the course of the following description.

30 In the drawings—

Figure 1 is a vertical sectional view of the invention, partly shown in side elevation and showing a fragment of the water or other heater.

35 Fig. 2 is a top plan view of the oil distributor.

Fig. 3 is a side elevation of the distributor.

In proceeding in accordance with the present invention, a base 1 is employed from which vertical supports or uprights 2 project. A ring 3 suitably supported at the top of the burner, has depending arms 4 and a saucer or cup like part 5, the arms 4 being secured by means of bolts 6 passing through slots 6 formed in the uprights 2, whereby to allow the upper portion of the device to be vertically adjusted so as to position the flame as desired with relation to the heater.

A vertical shaft 7 has a fan 8 secured to its upper end, and the extremity of its upper end rigidly secured to a rotatable oil disk 9. The lower end of the shaft is supported in the base 1 by means of the ball bearings 10 and 10', the latter being a truss bearing for carrying the weight of the shaft and the parts borne by the latter.

The shaft is rotated by means of a pulley 11 affixed thereto and a belt 12 which extends around the pulley and may in turn be driven by any means, such as an electric motor, not shown.

Oil is supplied by means of a pipe 13 which enters the heater near the bottom thereof, extends vertically and has a top branch 13' which overlies the ring 3, and discharges oil over the periphery of a distributor or deflector 14, which latter is disposed at the center of the oil disk 9. As depicted particularly in Fig. 2, the distributor has a series, preferably four, of oil passages or cutouts at its top, while the remainder or lower portion of the distributor is of somewhat bell shape so that the oil will be spread in flowing down over the distributor after leaving the passages 15 and entering the disk 9 will be consumed there.

The oil supply pipe 13 has a valve 16 to which latter is connected an upwardly extending arm 17 carrying a weight 18. A wire or other suitable connection 19 extends upwardly from the arm 17, and is connected to a fusible link 20, which latter is supported preferably by a pin 20' carried by the oil disk, though the link can be otherwise appropriately supported.

A jacket 21 formed of sheet metal properly coated with fire resisting material is supported from a ledge 22 projecting outwardly from the periphery of the ring 3, the upper end of the jacket being inturned so as to seat on the ledge 22 and receive support therefrom. This jacket functions to prevent air passing upwardly and cooling the water legs of the heater, since it acts to direct or positively guide all air entering the base of the structure to pass upwardly and inwardly and through the products of

combustion or through the flame chamber to supply oxygen to increase combustion.

The operation is as follows:

Power being applied to the belt 12, will effect rotation of the shaft 7, and there-through rotation of the fan 8 and the oil disk 9. Oil entering the supply pipe 13 will flow over the distributor 14 and into the disk 9, and since the disk 9 has perforations or openings 23, air will be forced by the fan upwardly through these openings so as to cause the flame of the burning oil to be forced upwardly and through the heater, to thereby heat the water. If for any reason the shaft should cease rotation, for example, due to breakage or disengagement of the belt 12, the flame will descend from the oil disk 9 through the holes 23 in the latter and will ignite any oil which may have accumulated in the drip pan 5, with the result that the fusible link 20 will be melted, thereby releasing the arm 17, so that the weight 18 will respond to the force of gravity and descending move the arm 17 to a position closing the valve 16 and thereby shutting off the oil supply. It will be thus apparent that an automatic shut-off for the oil supply is provided in event of stoppage of the fan. The fan operating means is also disposed at the base of the structure and at a distance from the flame so as to be not affected by the heat.

Since the supply head 14 is fixed, any adjustment of the burner by means of the bolts 35 6' will necessarily vary the distance between the head and burner.

Having thus described my invention, what I claim as new and desire to secure by Letters Patent is—

40 1. In an oil burner, a vertical shaft having a fan, a drip pan below the fan and oil disk above the fan, the oil disk being perforated so that its perforations align with the pan, an oil supply for the disk discharging at the center thereof, a ring encircling the disk and having a peripheral ledge, a jacket supported at its upper end from the ledge and being flared downwardly so as to encompass the fan and pan to thereby cause all air accessible to the parts from below to pass through the perforations of the oil disk, and means to drive the shaft.

55 2. In an oil burner, an oil disk, and an oil distributor therefor consisting of a bell-shaped element disposed with its base over the center of the disk and having a series of vertical oil passages spacedly disposed at the upper end of the bell-shaped element and terminating at a distance above the base thereof.

60 3. In an oil burner, oil burning means, an oil supply for said means, rotatable means to supply air to the oil burning means, means

to rotate the air supplying means, and heat-responsive means whereby upon cessation of 65 rotation of the air supplying means the oil supply will be automatically shut-off.

4. In combination with an oil burner and oil supplying means therefor, a fan associated with the burner, means to rotate the 70 fan, fusible means for shutting off the oil supply upon stoppage of the fan, and means whereby upon the fan stoppage the heat from the burner will be brought into contact with the fusible part of the fusible means. 75

5. In combination with an oil burner, an oil supply pipe having a cut-off valve therein, a weight for moving the valve to cut off position, means to support the weight inoperative, including a fusible link, a fan associated with the burner, means to rotate the fan, and means whereby upon stoppage of the fan rotating means the heat from the burner will be brought into contact with the fusible link so as to release said means holding the weight inoperative. 80

6. In combination with an oil burner and a rotatable fan associated therewith, oil supplying means for the burner, and heat-responsive means whereby upon stoppage of 90 the fan rotation said oil supplying means will be automatically shut off.

7. In combination with an oil burner, a base, a shaft journaled in the base and carrying the oil burner, a ring encircling the burner, an arm depending from the ring, a vertical support extending upwardly from the base, means to adjustably connect said arm to the vertical support, and means to drive the shaft in all adjustments of the arm. 95

8. In combination with an oil burner, a base, a shaft journaled in the base and carrying the oil burner, a support depending from the burner, an upright on the base, means to adjustably connect the support of the oil burner to said upright, and means to drive the shaft in all adjustments of the burner support. 105

9. In combination with a perforated oil burner and means to supply oil thereto, a fan below the burner, a drip pan below the fan to catch the oil drippings, a fusible link disposed adjacent the pan, and means whereby to cut off the oil supply controlled by said link upon stoppage of the fan. 110

10. In combination with an oil burner, a base, a support depending from the burner, an upright on the base, a relatively fixed supply head overlying the burner, and means to adjustably connect the support of the oil burner to said upright so as to vary the relation of the supply head to the burner. 120

11. In an oil burner, a supply pipe having a threaded part, and a bell-shaped oil distributor having its apex threaded into said 125 threaded part of the supply pipe and having

oil passages to allow the oil to flow past the threads of the threaded part of the supply pipe.

12. In an oil burner, a ring, a burner rotatable within the ring and having perforations, a peripheral ledge on the ring and a jacket having its upper end turned inwardly and engaged with said ledge and depending from the ring to direct all air accessible to

the burner from below through the perforations of the burner.

In testimony whereof I have signed my name to this specification in the presence of two subscribing witnesses.
